UNITED STATES PATENT OFFICE.

GILDEROY O. BURLEW, OF NEWARK, NEW JERSEY.

MEANS FOR PROTECTING FILLINGS FROM MOISTURE.

Application filed August 6, 1924. Serial No. 730,511.

To all whom it may concern:

Be it known that I, GILDEROY O. BURLEW, a citizen of the United States, and residing at Newark, in the county of Essex and State of New Jersey, have invented new and useful Improvements in Means for Protecting Fillings from Moisture, of which the following is a specification.

This invention relates to improvements in coverings possessing the properties of pliability, ductility and imporosity, capable of a broad general application and more particularly to temporary coverings to protect newly applied tooth fillings from moisture and retain them in proper condition free from outside interference.

In dental operations for the purpose of filling cavities, it is essential that the wall of the cavity be not only meticulously clean, but absolutely dry and that the cementlike filling employed be positively protected from moisture until it has set or become hardened; due to the natural flow of saliva and the strong tendency of persons under treatment to touch the teeth with the tongue, which it is difficult to restrain, and the abnormal position of the jaws in maintaining the mouth open for any considerable period of time, such desirable dryness is hard to keep inviolate.

One of the important objects of the invention is in the provision of a covering easily applied to the tooth or teeth being operated upon, the covering being self adherent, occupying no appreciable space in the mouth, allowing it to be closed with perfect ease, and which effectively prevents contact of the tongue or lips to the filling and further, is impervious to moisture.

Another purpose is to produce a covering that will retain its position as long as may be required without physical discomfort to the person operated upon, and which may be stripped off at will and thrown away, its cost being negligible.

These several aims and objects, together with others which will become manifest as the specification progresses, are accomplished by the simple and novel construction and combination of parts and selection of materials as hereinafter described and illustrated in the annexed drawing, forming part hereof, and in which:—

Figure 1 is a fragmentary perspective

view of a partial set of teeth, showing the 55 application of one embodiment of the invention.

Figure 2 is a plan view of a fragment of the covering in commercial form and illustrating the several layers of its composition. 60

Figure 3 is an enlarged transverse sectional view of the same.

Referring now more in detail to the drawing, Figure 1 shows several teeth, designated generally by the numeral 10 which, for the 65 purpose of illustration, may be supposed to be undergoing treatment that requires complete exclusion of moisture; this is attained by enshrouding the teeth with a cover generically indicated at 11.

The casing is composed of a laminated sheet, the outer layer 12 being a thin metallic foil, such as tin, easily yielding under pressure of the finger and readily conformable to fit the contour of the teeth and remain on them, covering the crown, labial and lingual surfaces from the outer to the inner side of the gum and spaces between adjacent teeth including all sinuosities.

Deposited on the foil is a film or layer 13 80 of paraffine or similar waxy substance united by heat to resist separation, short of physical force, and on the outer surface of the paraffine is a coating of finely ground gum tragacanth, rolled or pressed into the paraffine so as to become substantially inseparable.

The covering material is cut from a strip or sheet to such size and shape as may be required and applied to the teeth when in a 90 dry condition, and pressed by the fingers of the operator to closely engage the teeth with the gummed side thereagainst, the gum acting to maintain a firm adherence.

The lower edges of the covering may 95 slightly overlap the gums, which form a tight joint, preventing the entrance of saliva or other liquids for such time as may be desired, and thereafter the covering may be readily stripped off, leaving the teeth in a 100 dry and clean condition.

Should a small portion of the powdered gum tragacanth adhere to the surfaces of the teeth, it will rapidly become dissolved and disappear.

Although the foregoing is descriptive of the invention in its preferred embodiments, it is to be understood that the materials

used may be varied in accordance with requirements, and also the proportions and sizes of the same, without affecting the spirit and scope of the appended claims.

5 Having thus described the invention and set forth the manner of its manufacture and application, what I claim as new and desire to secure by Letters Patent, is:—

1. A dental material comprising a tin foil 10 covered on one side with paraffine and an adhesive coating on the paraffine.

2. A dental material comprising a tin foil covered on one side with paraffine, and a coating of powdered gum tragacanth incorporated on the surface of the paraffine.

3. A dental material for temporarily covering teeth to keep out moisture, comprising a pliable moisture proof sheet of metallic foil, a waxy coating on one side of said 20 sheet, an adhesive blended with said coating, said covering being sufficiently ductile to closely fit the sinuositites of the tooth to which it is applied.

4. A dental material comprising a metallic 25 foil covered on one side with paraffine and an adhesive coating on the paraffine.

5. A dental material comprising a foil covered on one side with paraffine and a

coating of powdered gum incorporated on the surface of the paraffine.

6. A dental material for temporarily covering teeth to keep out moisture, comprising a sheet of moisture proof foil, a waxy coating on one side thereof, and an adhesive blended with said coating, said material being sufficiently ductile to closely fit over the teeth to which it is to be applied.

7. A dental material comprising a sheet of metallic foil covered on one side with an adhesive wax substance.

8. A dental material formed of a sheet of tin foil covered on one side with paraffine and having an adhesive coating on the paraffine.

9. A dental material comprising a metallic foil covered on one side with paraffine and a coating of powdered gum incorporated on the surface of the paraffine.

10. A dental material comprising a tin foil covered on one side with paraffine and an adhesive coating of gum tragacanth on the surface of the paraffine.

This specification signed and witnessed this 30th day of July, 1924.

GILDEROY O. BURLEW.
